No. 659,211.

Patented Oct. 9, 1900.

J. W. COMBS.
STOVEPIPE FASTENER.
(Application filed Jan. 19, 1900.)

(No Model.)

UNITED STATES PATENT OFFICE.

JOHN WILLIAM COMBS, OF PRINCETON, MISSOURI, ASSIGNOR OF ONE-HALF
TO JAMES A. THOMPSON, OF SAME PLACE.

STOVEPIPE-FASTENER.

SPECIFICATION forming part of Letters Patent No. 659,211, dated October 9, 1900.

Application filed January 19, 1900. Serial No. 2,014. (No model.)

To all whom it may concern:

Be it known that I, JOHN WILLIAM COMBS, a citizen of the United States, residing at Princeton, in the county of Mercer and State 5 of Missouri, have invented a new and useful Stovepipe-Fastener, of which the following is a specification.

This invention relates to stovepipe-fasteners, and has for its object to provide improved 10 means for securing a stovepipe-section within the flue-opening of a chimney. It is furthermore designed to provide an adjustable device of this character which may be accommodated to chimney-walls of different thicknesses and also to pipe-sections of different 15 lengths, and, finally, to prevent the inner end of the stovepipe from being accidentally forced into the chimney-flue and also to prevent outward displacement of the pipe-section. 20

To these ends the present invention consists in the combination and arrangement of parts, as will be hereinafter more fully described, shown in the accompanying drawings, 25 and particularly pointed out in the appended claim, it being understood that changes in the form, proportion, size, and minor details may be made within the scope of the appended claim without departing from the spirit or 30 sacrificing any of the advantages of the invention.

In the drawings, Figure 1 is a longitudinal sectional view showing the present invention supporting a stovepipe-section in a flue-opening 35 of a chimney. Fig. 2 is a detail perspective view of the improved fastening device.

Corresponding parts in both figures of the drawings are designated by like characters of reference.

Referring to the accompanying drawings, 1 designates the main bar of the device, which is formed of flat strap metal and is provided at its outer end with an inwardly-disposed hook 2, formed by bending the end of the bar 45 inwardly upon the inner or under side of the bar. From the opposite or inner end of the bar extend opposite longitudinal flanges 3, which terminate short of the outer hooked end of the bar, and the latter is provided with a longitudinal slot 4, located between the flanges. 50

Mounted to slide upon the outer side of the

main bar and between the flanges thereof is a supplemental bar 5, also formed of flat strap metal and having its inner end provided with an upstanding and outwardly-disposed clamp- 55 shoulder 6. Located opposite this shoulder and extending inwardly upon the inner side of the supplemental bar is a hook 7. A substantially L-shaped wall-clamp 8 is slidably mounted upon the outer side of the supplemental bar and between the flanges of the main bar and is provided with a longitudinal slot 9, formed in the body of the clamp, which is in engagement with the supplemental bar. 60

From the foregoing description it will be apparent that the several parts of the device are slidable longitudinally upon each other, and in order to fix the parts at any point of adjustment there is provided a headed screw-threaded fastening 10, carried by the supplemental bar and projecting in opposite directions through the slots of the main bar and the wall-clamp, the head of the fastening being located against the inner side of the main bar. The outer end of the fastening projects outwardly through the slot in the wall-clamp, so as to receive a suitable thumb-nut 11, whereby the parts may be held at any adjustment, as will be understood. 75

In the application of the device the inner 80 end thereof is thrust through the flue-opening 12 of a chimney 13 and the clamp-shoulder 6 engaged against the inner side of the front wall thereof. Afterward the outer wall-clamp 8 is adjusted to engage against 85 the outer wall of the chimney, so as to support the fastener upon the latter. Then the stovepipe-section 14 is placed in the flue-opening and its inner edge or end engaged with the inner hook 7, as clearly shown in 90 Fig. 1 of the drawings, and finally the outer hook 2 is engaged with the outer end of the stovepipe. Thus it will be seen that the fastener is secured to the wall of the chimney and the pipe-section is secured to the device, 95 the inner hook 7 preventing the inner end of the pipe from being accidentally pushed into the chimney-flue and the outer hook 2 preventing outward displacement of the stovepipe. It will also be apparent that the several parts are independently adjustable, so 100 that the clamp members may be accommo-

dated to chimney-walls of different thicknesses, and also the supplemental bar may be adjusted longitudinally upon the main bar, so that the device may be fitted to stove-pipe-sections of different lengths. To provide for a greater range of adjustment, the supplemental bar may be provided with one or more additional openings 15 for the reception of the fastening 10, as will be understood. Moreover, the device is located exteriorly of the stovepipe, and therefore does not interfere with the draft therethrough and does not require any change in the pipe or the formation of perforations therein.

15 What I claim is—

In a stovepipe-fastener, a main bar, having its outer end bent or folded into a hook, opposite longitudinal flanges upon the opposite side of the bar from the hook, and also a longitudinal slot located between the flanges, a supplemental bar slidable longitudinally upon the main bar and between the flanges thereof, and also projecting longitudinally at the inner end of the main bar, an outwardly-extending clamp-shoulder provided at the outer projecting end of the supplemental bar, and

an inwardly-directed hook located upon the inner side of the outer end of said bar, the latter also having a plurality of perforations, a substantially L-shaped wall-clamp slidable 30 upon the outer side of the supplemental bar and between the flanges of the main bar, cooperating with the outwardly-directed clamp-shoulder, and also provided with a longitudinal slot, a headed screw-threaded fastening 35 carried by the supplemental bar and projecting through one of the perforations thereof, the head of the fastening being located upon the outer side of the main bar and the adjacent shank portion being slidable in the slot 40 of the main bar, and a nut provided upon the outer projecting end of the fastening and to bind against the outer side of the L-shaped clamp.

In testimony that I claim the foregoing as 45 my own I have hereto affixed my signature in the presence of two witnesses.

JOHN WILLIAM COMBS.

Witnesses:

GRANT DUBLE,
G. W. MILLER.
